UNITED STATES PATENT OFFICE.

JOHN A. DALY, OF NEW ROCHELLE, NEW YORK.

DEVICE FOR CLEANING TEETH.

1,230,683.

Specification of Letters Patent. Patented June 19, 1917.

Application filed November 6, 1916. Serial No. 129,748.

To all whom it may concern:

Be it known that I, JOHN A. DALY, a citizen of the United States, residing at Rochelle Park, New Rochelle, in the county of 5 Westchester and State of New York, have invented certain new and useful Improvements in Devices for Cleaning Teeth, of which the following is a specification.

This invention relates to devices for cleaning the teeth, and more particularly that 10 class of such devices which are adapted to be placed upon the tip of the finger and held thereon by means of the elasticity of the teeth cleaning member, and it has for its 15 primary object the provision of such a device in which the elastic member is provided with an additional cleaning and polishing surface formed of suitable flexible material adapted to form a secondary finger cot to 20 overlie the elastic finger cot which fits the finger tip.

A further object of the invention is to 25 provide a finger cot of the character set forth with means to prevent any constriction of the tip of the finger and to permit circulation of air around the tip of the finger incased by said finger cot.

A still further object of this invention is 30 to provide a modified form of the device more particularly adapted for use in hospitals or other institutions where the user thereof is suffering from an infectious or contagious disease, whereby the teeth-cleaning portion of the device may be removed 35 and thrown away after the device has been used.

With the foregoing and other objects in 40 view as will from time to time hereinafter appear this invention consists in the particular combination and arrangement of the various parts of a device for cleaning the teeth as described in the following specification and more particularly set forth in the appended claims.

45 Referring to the accompanying drawings illustrating the essential features of the invention and in which the same reference characters indicate the same parts wherever used,

50 Figure 1 is a perspective view of the preferred embodiment of the device;

Fig. 2 is a longitudinal section of an enlarged scale of the device shown in Fig. 1;

55 Figs. 3 and 4 are views of modified forms, and

Fig. 5 is a cross section on an enlarged scale of the device shown in Fig. 4.

6 designates the ordinary form of rubber finger cot tooth-brush which is provided with a plurality of upstanding teeth-cleaning projections 7, the said finger cot being adapted to be worn upon the end of a finger and to be used in this position to clean the teeth. The forward end of the member 6 is provided with a small aperture 8 which permits the egress of air from the interior of the member 6 when the same is placed upon the finger, thus permitting the member to slide easily upon the finger and to set firmly in place.

In accordance with the present invention a second member 9 similar to the member 6 but formed of suitable textile material adapted to present a rough surface, is placed over the member 6, the projections 7 of 75 which project upwardly through the textile covering 9 with a portion of their length projecting above the surface of the textile fabric.

In the modification shown in Fig. 3, the 80 finger cot 6 is incased by means of a second finger cot 9 formed of similar textile material but of closer weave than that in the construction illustrated in Figs. 1 and 2, so that the projections 7 do not project through the 85 member 9 but are incased thereby.

In the modifications shown in Figs. 4 and 90 5, the construction of the member 6 is modified so that the underside thereof is provided with a plurality of longitudinally extending convolutions 10 which permit a circulation 95 of air between the finger cot 6 and the finger incased thereby, in order to prevent any constriction of the finger by the elastic portion 6. In the construction of the other two 95 forms of this invention the finger cot 6 is incased by a second finger cot 9 of suitable flexible material.

The operation of the device is as follows:

In the constructions shown in Figs. 1 and 100 2 the device is placed upon the end of the finger as described and the teeth cleansed by means of the projections 7 acting in conjunction with the adjacent textile surface of the member 9 when the teeth may be polished 105 by using the reverse or underside 11 of the device which is free from the projections 7, and which presents only the textile surface. In the constructions shown in Figs. 3 to 5 the operation of the device is the same with 110

the exception that the second cot 9 may be removed and thrown away after each use.

I realize that considerable variation is possible in the details of construction and ar-

5 arrangement of parts without departing from the spirit of my invention, and I therefore do not intend to limit myself to the specific form shown and described.

Having thus described my invention what 10 I claim as new and desire to secure by Letters Patent is:

1. In a device for cleaning the teeth, the combination with a finger cot provided with a plurality of teeth cleaning projections ex-

15 tends therefrom, of a second cot adapted to incase said first named cot and to be held thereon by said projections.

2. In a device for cleaning the teeth, the combination with a finger cot having a plu- 20 rality of teeth cleaning projections thereon,

of a second cot adapted to incase said first named cot, the projections of said first named cot passing through interstices in the second named cot to hold the same in position.

3. In a device for cleaning teeth, the combination of an elastic finger cot adapted to incase the end of a finger and provided on one side with a plurality of corrugations to reduce the pressure upon the finger and having on its outer surface a plurality of teeth 25 cleaning projections extending therefrom and a second cot of textile material adapted to incase said first named cot and be held in place by said projections.

In testimony whereof I affix my signature 30 in presence of two witnesses.

JOHN A. DALY.
